UNITED STATES PATENT OFFICE

2,435,540

ADJUSTABLE PITCH PROPELLER

Gordon W. Hardy, Euclid, Ohio, assignor to The Marquette Metal Products Company, Cleveland, Ohio, a corporation of Ohio

Application November 15, 1945, Serial No. 628,772

18 Claims. (Cl. 170—162)

1

This invention relates to adjustable pitch propellers and particularly to a new and improved hub therefor.

In adjustable pitch propellers, the usual practice is to provide a suitable hub and detachable blades and then to assemble the blades and the hub, balancing the assemblage carefully about its axis of rotation and setting the pitch of the blades and securing them in adjusted position. Considerable difficulty has been encountered in obtaining both proper balance and pitch, particularly the former, and as practiced at present, this operation is expensive and time consuming.

One of the principal objects of the present invention is to provide a new and improved propeller hub in which the blades can be installed and balanced easily and accurately and, then, without disturbing the balance, can be adjusted to proper pitch.

Another object is to provide a propeller having a hub and blades which can be readily assembled and in which the blades can be installed easily, accurately balanced about the rotative axis, held securely at the pitch selected, released easily when desired for adjustment to different pitch angles and securely relocked at a different pitch angle without disturbing the balance of the assembled propeller.

Another object is to provide a rigid and durable hub which embodies features making the above objects attainable and which, at the same time, is rugged and durable.

A more specific object is to provide a hub in which most of the component parts are cylindrical or circular as a whole and configured as to details so that the complementary surfaces of the parts of the hub and also the surfaces of the interfitting shanks of the blades can be machined and ground efficiently and accurately.

Another specific object is to provide a hub having an adjustable spacer therein for spacing the shanks of the blades properly from each other for balancing the propeller and for aligning the axes of the blade shanks during assembly and balancing the propeller.

Other features and advantages will become apparent from the following description wherein reference is made to the drawings in which

Fig. 1 is a side elevation of a propeller embodying the principles of the present invention, part thereof being shown in section for clearness in illustration;

Fig. 2 is a side elevation of an embodiment of the adjustable spacer of the hub of the propeller illustrated in Fig. 1;

2

Fig. 3 is a longitudinal sectional view of the adjustable spacer and is taken on line 3—3 of Fig. 2;

Fig. 4 is a cross sectional view of one of the ends 5 of the tubular connector of the hub with a propeller blade shank mounted therein, and is taken on line 4—4 of Fig. 1;

Fig. 5 is a perspective view of a locking key of the present invention;

Fig. 6 is a longitudinal view of a modified form 10 of propeller hub for use with a tapered drive shaft; and

Fig. 7 is a cross sectional view of the hub illustrated in Fig. 6 and is taken on line 7—7 of Fig. 6.

Referring to the drawings, the invention is shown, for purposes of illustration, embodied in an adjustable pitch propeller, in which any pitch setting desired is made while the propeller is stationary as distinguished from a variable pitch propeller in which the pitch of the blades can be varied while the propeller is being driven during flight, the application of the invention to variable pitch propellers being readily apparent from the illustrative example.

As best illustrated in Fig. 1, the assembled propeller includes a hub, designated generally at 1, which is connected to the usual impeller or drive shaft 2 of an engine, and carries propeller blades 3.

The hub 1 comprises a tubular retaining body 4 which preferably is cylindrical and a tubular connector 5 which also preferably is cylindrical and which extends diametrically through the retaining body 4 at a location preferably equidistant from the ends of the body 4. The end portions of the connector 5 extend radially outwardly beyond the body 4 so as to be readily accessible for the reception of shanks of the propeller blades 3 and for locking of the blade shanks thereto, as is hereinafter described.

The end portions of the connector 5 are internally threaded from their outer ends inwardly partway of their length, as indicated at 6, and the inner wall of the connector 5 is finished accurately to true cylindrical form preferably for the entire distance between the threaded portions at its outer ends, thus providing an axial bore 7.

Each of the blades 3 has a shank 8 which is generally cylindrical but is provided with external annular indentations 9 and 10. A segmental retainer or anchor ring 13 having internal annular ribs 11 and 12, which are complementary to the indentations 9 and 10, respectively, is provided for each shank for securing the associated shank in the connector 5 against axial movement

while permitting the shank to be rotated about its axis.

The retainer 13 preferably is made in congruent halves and its outer surface is finished to fit accurately into the cylindrical bore 7 when the halves are fitted onto the shank 8 of the blade. The ring 13, when installed, forms in operative effect a part of the shank 8, being rotatable therewith and fixed in position axially thereof.

In order to anchor the blades 3 in the ends of the connector 5, each retainer 13 is of larger external diameter than the associated shank 8 so as to provide an annular locking shoulder 14 which faces toward the adjacent outer end of the connector 5. An externally threaded castellated collar 15 slidably and rotatably embraces the shank 8 outwardly from the retainer 13 and engages the complementary threaded portions 6 of the connector 5. By engagement of the inner end of the collar 15 with the shoulder 14 of the retainer 13, the blade 3 is anchored against movement outwardly axially of the connector 5 but can be rotated about said axis. For locking the blade against rotation about the longitudinal axis of the connector 5, the outer ends of the connector 5 are castellated, as indicated at 16, and a suitable key 17 is interfitted with aligned notches of the castellations 16 and those of the castellated collar 15. The key 17 is held in position by means of an external clamping ring 18 secured by a bolt 19. Due to the castellations of the retaining collar 15, the outer end of the castellated portion can spring and act as gripping jaws when drawn tightly against the propeller blade by the clamping ring 18, thus effectively clamping the propeller blades in properly adjusted pitch position.

In order to provide for locking the blades in a large number of relatively rotated positions about their longitudinal axes, so as to permit very fine adjustments for balance, the notches of the castellations 16 of the connector 5 are angularly disposed about the longitudinal axis of the connector 5 at different angles than are those of the collar 15 thus providing a Vernier effect in aligning any notch of the collar 15 with a notch of the connector 5. For example, an even number of notches may be provided in each end of the connector 5 and an odd number in the associated collar 15. In the form illustrated, nine notches are provided in each end of the connector 5 and four in each collar. With this arrangement, the adjustment of a blade axially of the connector 5 for balance is independent of the adjustment of the other blade and the adjustment of a blade rotatively of the axis of the connector 5 for pitch is independent of the rotative adjustment of the other blade. Also, the axial and rotative adjustments of a single blade are independent of each other.

Adjacent its inner end, each shank 8 has an external annular pilot area 20.

Mounted within the connector 5 is a rigid spacer 21 which is preferably a single tube as illustrated in Figs. 2 and 3. The tube may be split longitudinally in case the impeller shaft 2 is of the tapered, keyed type, as illustrated in Figs. 6 and 7. The spacer 21 is ground or otherwise finished accurately on its outer surface near its ends so as to slip into the bore 7 with sliding fit clearance. The spacer has to be slidable axially of the connector 5 short distances while held in accurate coaxial relation thereto. Its ends are accurately finished to provide annular seating

areas 22 for operative engagement with complementary seating areas 23 of the shanks 8. In the illustrative example herein, instead of forming the complementary seating areas directly on the shanks, the seating areas of the shanks are formed on the inner ends of the retainers 13 which are fixed axially of the respective shanks and form parts thereof.

The spacer 21 is finished to a very accurate length so that when the seating areas 23 of the shanks 8 are in engagement with the seating areas 22 of the spacer, the blade shanks, and therefore the blades themselves, are accurately positioned the proper distance from each other axially of the connector 5.

As mentioned, the spacer 21 is slidable axially in the bore 7 of the connector 5 and is accurately guided therein. The spacer 21 is provided with a plurality of transverse openings 24 and large aligned diametral openings 25, for purposes later to be described.

Within the ends of the retaining body 4 are front and rear cover plates 26 and 27, respectively, the plates 26 and 27 being machined peripherally and the inner ends of the retainer body 4 being machined complementary to those of the plates 26 and 27 so that the plates interfit accurately with the ends of the retaining body 4. The rear plate 27 is peripherally integrally connected to the retaining body 4 by welding at 27' so as to form substantially a unitary structure therewith. The rear plate 27 preferably is of sufficient thickness so that when fitted into the end of the retaining body 4, its inner face 30 lies close to but spaced from the nearest portion of the circumferential surface of the connector 5 at diametrically opposite sides of the shaft 2. Along these areas of near contact and for a material distance each side thereof, circumferentially of the connector, the plate 27 is permanently integrally joined to the connector 5, by welding, as indicated at 28. The space resulting from the spacing of the plate 27 and connector 5 and that resulting from the curvature of the connector 5 away from the planar inner face of the plate 27 are filled in with the welding metal for a material distance each side of the region of near contact. The plate 26 may be similarly welded or integrally connected to the retainer body 4 if desired, but generally is left unwelded so that it may be removed easily.

Likewise, as illustrated in small part at 29, the retaining body 4 is permanently integrally connected to the connector 5 where the connector 5 intersects the circumferential wall of the retainer 4, preferably by welding.

Aligned openings 30 are formed in the plates 26 and 27 for receiving suitable tie-bolts 31 and cooperating clamping nuts 32. The nuts 32 are cylindrical so as to fit accurately in the openings 30 of the plate 27 and openings 33 of the connector and each has a flange head with flats for engagement by a wrench. Part of the bolts 31 extend through the connector 5 and part are spaced therefrom.

Because of a number of the bolts passing through the connector 5 suitable openings 33 are provided therein, these openings and the openings 24, heretofore described, of the spacer 21 are alignable with each other, the openings 24 of the spacer being made larger than the bolts which extend therethrough so as to permit adjustment of the spacer 21 axially of the connector 5 after the bolts are inserted. The diametral openings

25 of the spacer 21 are for the purpose of accommodating with clearance the inwardly extending end of the drive shaft 2, and, temporarily, a balance testing bar or mandrel.

In order to fasten the hub to the drive shaft 2, a suitable flange 34 is provided on the drive shaft and has suitable openings, as illustrated, for accommodating snugly the nuts 32 of the clamping bolts 31. In order to prevent distortion of the plates 26 and 27 when the bolts are drawn tightly into place by the bolts 31, suitable thin walled tubular spacing sleeves 35 are provided for embracing those bolts which are offset from the line of near contact of the plate 27 and the connector 5 and suitable spacing discs 36 are provided between the plate 26 and the connector 5 in embracing relation to those of the bolts 31 which intersect the tubular connector 5. The usual forward streamlining cover 37 is provided and is secured to the outer peripheral wall of the tubular retaining body 4.

It is apparent from the foregoing description that when the blades 3 are initially installed in the ends of the connector 5, with the spacer 21 operatively interposed therebetween with the seating areas 22 and 23 in engagement that the blades may be moved into place axially of the spacer 5 while the hubs are at all times maintained in properly spaced relation endwise of the connector 5 with respect to each other.

The plates 26 and 27 are provided with large central openings 38. The connector 5 is provided with a pilot opening 39 extending transversely thereof and a diametrically aligned larger pilot opening 40 through which the shaft 2 may pass.

In order to balance the propeller, a suitable mandrel, not shown, is inserted in the propeller hub and accurately fits the openings 39 and 40 and extends beyond the plates 26 and 27. The mandrel is laid on a suitable horizontal track so that the propeller is free to rotate about its axis and roll along the track if any unbalance exists. In case any unbalance is found, it is necessary only to loosen the clamping rings 18, remove the keys 17, and then loosen the castellated collar 15 of one blade and, at the same time, tighten the castellated collar 15 of the other blade so as to hold the blades firmly against the spacer 21 and shift them as a unit axially of the connector 5 without changing the pitch. When the axial adjustment is completed, the blades may be set accurately, one at a time, in the proper rotated pitch position about the axes of their shank without disturbing the balance by slightly loosening the castellated collar of one blade at a time while retaining the collar 15 of the other tight. This is effective because, by holding tightly against the spacer 21 the blade which is being adjusted for pitch, the balance is not disturbed. Thereupon suitable match marks may be made on the blade and connector 5. Thereafter the collars 15 can be tightened without disturbing the alignment of the match marks or the pitch of both blades can be reset when desired merely by reference to the match marks. The blades are set approximately at the proper pitch adjustment before balancing the propeller so that the final pitch adjustment does not disturb the final balance.

When the balance and pitch is thus set, the keys 17 are inserted in a pair of properly aligned notches of the castellations of the collar 15 and castellations 16 of the tubular connector 5 after which the retaining collars 18 are clamped tightly in place.

In assembling the hub, the tubular connector 5 is properly centered endwise in the transverse openings of the retaining body 4 and these two parts are then welded together circumferentially of the connector 5, internally or externally of the body 4, or both. Next, the cover plate 21 is fitted into place and welded about its periphery to the retaining body 4 and welded to the connector 5 along and adjacent the line of near contact. The plate 21 is fitted into place and the bolt holes 30, heretofore described, are drilled through the plates 26 and 27, using a suitable jig and the center holes. The axes of two sets of aligned holes 30 so formed for the bolts 31 diametrically intersect the tubular connector 5 and complementary holes 33 are made in this same operation. All six of the holes 30 in the back plate and the adjacent holes in the connector 5 are then enlarged, using the previously made holes as pilots so as to receive the cylindrical attaching nuts 32 such as commonly employed in the crankshaft assembly, or the tubular spacing sleeves 35. The pilot holes 39 and 40 are drilled after assemblage as also are the central openings 38. If desired, additional holes 41 may be provided in the spacer 21 for reducing weight.

Referring next to Figs. 6 and 7, a modification of the hub for use with tapered propeller shafts, is illustrated. As there illustrated, the propeller shaft 50 has a tapered end portion 51 with a longitudinal keyway 52 and is threaded at its extreme end, as indicated at 53, to receive a jam nut 54. The connector 55 is similar to the connector 5 except for the large central aligned diametral holes 56 and 57 of the connector 55.

A rear end plate 58, corresponding to the plate 21, is provided and has an integral internally tapered socket portion 59 which is coaxial with the plate and receives the tapered portion 51 of the shaft 50. The holes 56 and 57 are arranged so that the tapered socket portion 59 fits accurately therein. The annular retaining body 60, corresponding to the retaining body 4 accommodates the plate 58 and is welded thereto peripherally of the plate, as indicated at 61. Excess welding stock is faced off flush with the rear face of the rear end plate when the latter is machine faced to true it with reference to the main propeller axis. The connector 55 is welded to the circumferential wall of the body 60 circumferentially of the connector, as indicated at 62, in the same manner as in case of the weld 29 heretofore described. The socket portion 59 passes through holes 57, as indicated at 63. No front cover plate 55 such as 26 in Fig. 1 need be used in the construction according to Fig. 6. The streamlining nose cap and all portions of the blade mounting assemblies are omitted from Fig. 6. The construction of the omitted parts is the same as in Fig. 1.

Since the socket portion 59 extends entirely across the connector 55 diametrically thereof, the spacer 64 is made in two congruent and complementary end sections 64a and 64b instead of in one piece, as is the spacer 21, the end portions 65 being separable at the longitudinal mid-portion of the spacer 64 on a plane at right angles to its diameter, as indicated at 66. The spacer has aligned openings 67 and 68 which accommodate the spacer 64 with radial clearance to permit adjustment of the spacer axially of the connector 55. By making the spacer 64 in two sections the spacer can be assembled in and from the connector readily after the plate 58 is installed. Due to its being made in two separable portions, the spacer 64 is provided with circum-

ferentially extending bearing ribs 69 of which the outer surfaces are in slip fitting engagement with the inner wall of the connector 55, as indicated at 70, and the adjacent inner ends of the portions 64a and 64b are finished to form complementary abutments or seats as indicated at 71. As a result of the seating of the portions in the connector, as at 70, and the seating of their ends, as at 71, they act, in so far as spacing is concerned, as a single unitary spacer, adjustable endwise of the connector 55. The spacer 64 may be made and machined in one piece, then cut into end portions and its inner ends finished to proper complementary seats. For purposes of the claims, the spacer 64 is considered as a unitary spacer the same as the spacer 21, except where specifically recited otherwise in the claims.

I claim:

1. A propeller hub comprising a tubular connector having its ends open and adapted to receive axially, and to accommodate slidably endwise of the connector, shanks of propeller blades, a tubular spacer within and coaxial with the connector and slidable endwise thereof to different adjusted positions, said spacer having seating areas facing toward the ends of the connector and adapted for seating engagement, when the shanks are received in the connector with complementary seating areas of the shanks, means on the connector adapted for connection to complementary means of the blade shanks for connecting the blade shanks in adjusted positions axially of the connector while the seating areas of the shanks and spacer are in seating relation to each other, and means for connecting the connector to a propeller shaft with the connector axis intersecting the shaft axis at a right angle.

2. A propeller hub comprising a tubular connector having its ends open and adapted to receive axially, and to accommodate slidably endwise of the connector, shanks of propeller blades, a tubular spacer fitting within and coaxial with the connector and slidable endwise thereof to different adjusted positions, said spacer having seating areas facing toward the ends of the connector and adapted for seating engagement concurrently with complementary seating areas of the shanks when the shanks are received in the connector, said spacer also having pilot surfaces extending generally lengthwise of the spacer for engagement with complementary pilot surfaces of the shanks for guiding the shanks into coaxial relation with the spacer and connector, means for connecting the shanks in fixed position in the connector, and means for connecting the hub to a propeller shaft.

3. A propeller hub comprising a tubular retaining body, a tubular connector extending diametrically therethrough and having its ends open to receive axially, and to accommodate for sliding movement endwise of the connector, shanks of propeller blades, a spacer fitting within and in coaxial relation to the connector and slidable endwise thereof, said spacer having seating areas facing generally toward the ends of the connector and adapted for engagement with complementary seating areas of the propeller blade shanks when the shanks are inserted in the connector, connecting means for connecting the blades to the connector in adjusted position of the blades axially of the connector and in adjusted pitch position, and means rigidly connected to the connector and to the retaining body and adapted for connection to a propeller shaft.

4. A propeller hub comprising a tubular retaining body, a tubular connector extending diametrically through the retaining body and having its ends open, each end of said connector being adapted to receive axially and snugly accommodate a propeller blade shank, means carried by the connector for securing the associated blade shank in adjusted pitch position and adjusted position axially of the connector, end plates in 10 and coaxial with the retaining body at opposite sides of the connector, at least one of said plates being permanently rigidly connected with the connector along a portion of its inwardly disposed face and permanently rigidly connected to the retaining body about its periphery, said plates having aligned sets of openings parallel to and offset from the axis of the retaining body, and bolts extending through said sets of aligned openings respectively for connecting the plates and connector to a propeller shaft.

5. A propeller hub comprising a tubular retaining body, a tubular connector extending diametrically through the retaining body, a tubular spacer within, coaxial with, and slidable endwise 25 of, the connector, each end of said connector being adapted to receive axially and to accommodate snugly a propeller blade shank, the tubular spacer having seating areas facing generally toward the ends of the connector and adapted to 30 abut complementary seating areas of the shanks, means carried by connector and operatively connectable to the blade shanks for securing the blade shanks independently in adjusted positions axially of the connector, end plates in and coaxial 35 with the retaining body at opposite sides of the connector, at least one of said plates being permanently rigidly connected to the connector along a portion of its inwardly disposed face and permanently rigidly connected to the retaining body 40 about its periphery, said plates having sets of aligned openings parallel to and offset from the axis of the retaining body, the connector having openings aligned with some of the plate openings, bolts extending through said sets of aligned openings 45 respectively for securing the hub to a propeller shaft, and said tubular spacer having enlarged diametral openings for affording passage of some of said bolts through the spacer in different adjusted positions of said spacer endwise 50 of the connector.

6. A propeller hub comprising a tubular retaining body, a tubular connector extending diametrically through the retaining body, a tubular spacer within, coaxial with, and slidable endwise 55 of, the connector, each end of said connector being adapted to receive axially and to accommodate snugly a propeller blade shank, the tubular spacer having seating areas facing generally toward the ends of the connector and adapted to 60 abut complementary seating areas of the shanks, means carried by connector and operatively connectable to the blade shanks for securing the blade shanks independently in adjusted positions axially of the connector, end plates in and coaxial 65 with the retaining body at opposite sides of the connector, at least one of said plates being permanently connected at its inner face to the connector and permanently connected at its periphery to the retaining body, said plates having sets of aligned openings parallel to and offset from the axis of the retaining body, the connector having 70 openings aligned with some of the plate openings, bolts extending through said sets of openings respectively for securing the hub to a propeller shaft, said tubular spacer having enlarged di-

ametal openings for affording passage of some of said bolts through the spacer in different adjusted positions of said spacer endwise of the connector, and spacer sleeves on part of the bolts for reinforcing the plates against distortion inwardly.

7. A propeller hub comprising a tubular retaining body, coaxial tubular connector means extending radially outwardly from the retaining body and having their ends open, each of said connector means being adapted to receive axially and snugly accommodate a propeller blade shank, means carried by connector means for securing the associated blade shank in adjusted position axially of the connector means, end plates in and coaxial with the retaining body at opposite sides of the connector means, at least one of said plates being connected with the connector means at its inwardly disposed face and being connected to the retaining body at its periphery, said plates having aligned sets of openings parallel to and offset from the axis of the retaining body, bolts extending through said sets of openings respectively for connecting the plates and connector to a propeller shaft, and said connector means being directly connected to the retaining body.

8. A propeller hub comprising a tubular retaining body, coaxial tubular connector means extending radially outwardly from the retaining body, each connector means being open at its ends to receive axially shanks of propeller blades and to accommodate said shanks for sliding movement axially of the connector means, a rigid spacer within and in coaxial relation to the connector means and guided therein at its ends for sliding endwise thereof, said spacer having seating areas facing generally toward the outer ends of the connector means and adapted for engagement with complementary seating areas of the propeller blade shanks when the shanks are inserted in the connector means, connecting means for connecting the blades to the connector means in adjusted position of the blades axially of the connector means, and means connected to the connector means and to the retaining body and adapted for connection to a propeller shaft.

9. A propeller hub comprising a tubular retaining body, connector means having coaxial tubular end portions extending radially outwardly through the retaining body and adapted to receive axially, and to accommodate slidable endwise of the connector means, shanks of propeller blades, a rigid spacer within and coaxial with the end portions of the connector means and slidable endwise to different adjusted positions, said spacer having seating areas facing toward the outer ends of the connector means and adapted for engagement, when the shanks are received in the connector, concurrently with complementary seating areas of the shanks, and means on the connector adapted for connection to complementary means of the blade shanks for connecting the blade shanks in adjusted positions while the seating areas of the shanks and spacer are in seating relation to each other, said connector means being rigidly connected to the circumferential wall of the retaining body, a plate coaxial with the body and peripherally connected thereto at one end of the body and having its inwardly disposed face connected to the connector means, and means for connecting the hub to a propeller shaft with the axis of the connector means intersecting the shaft axis at a right angle.

10. A propeller comprising a tubular connector having its ends open, propeller blades, shanks on

said blades fitting into said open ends and supported thereby in coaxial relation and for sliding movement independently axially of the connector, a rigid spacer fitting within and movable axially of the connector and having seating areas facing toward the ends of the connector, means on the shanks with seating areas in fixed relation axially of the shanks and complementary to those of the spacer, connecting means for interconnecting the shanks and connector in axially adjusted positions, and means for connecting the hub to a shaft.

11. A propeller comprising a tubular connector having its ends open, propeller blades, shanks on said blades fitting into said open ends and supported thereby in coaxial relation and for sliding movement independently axially of the connector, a spacer fitting within and movable axially of the connector and having seating areas facing toward the ends of the connector, means on the shanks with seating areas in fixed relation axially of the shanks and complementary to those of the spacer, connecting means for interconnecting the shanks and connector in axially adjusted positions, said connecting means including castellated collars embracing the shanks respectively and slidable axially thereof and having a coaxial threaded portion, said connector having a complementary threaded portion cooperable therewith, the ends of said connector being castellated, means cooperating with the castellation to lock the collar against rotation, and means for connecting the propeller to a shaft.

12. A propeller comprising a tubular connector having its ends open, propeller blades, shanks on said blades fitting into said open ends and supported thereby in coaxial relation and for sliding movement independently axially of the connector, segmental retaining collars surrounding a portion of the shanks, respectively, within the connector and interfitting with the shank for anchoring the retaining collar and shank against relative axial movement, said collars having radial shoulders of greater diameter than the shanks and facing toward the outer ends of the connector, means adjustable axially of and connected to the connector and engaging the shoulders for restraining the shanks from movement axially outwardly from their axially adjusted positions in the connector, and means for connecting the propeller to a shaft.

13. A propeller comprising a tubular retaining body, propeller blades, shanks on the blades, a tubular connector extending diametrically through the retaining body, and adapted to receive the shanks in its ends for supporting the blades, cover plates fitting into the ends of the retaining body and rigidly permanently connected to the retaining body about their periphery, at least one of said plates being adapted for connection with a propeller shaft in coaxial relation to the retainer, means connecting the plates to the connector for rotation therewith about the axis of the plates.

14. A propeller comprising a tubular retaining body, propeller blades, shanks thereon, a tubular connector connected to and extending diametrically through the retaining body and adapted to receive the shanks axially, cover plates fitting into the ends of the retaining body and rigidly permanently connected to the retaining body about their periphery, means connecting the plates to the connector for rotation therewith about the axis of the plates, means for

connecting the plates together and to a propeller shaft including bolts spaced about and parallel to the axis of said plates, each bolt being secured to both plates and spanning the distance therebetween, reinforcing sleeves on some of the bolts and engaging the plates at each of their ends, and means anchoring the other of the bolts directly to the connector.

15. A propeller comprising a tubular retaining body, propeller blades, shanks thereon, a tubular connector extending radially through the body, said shanks fitting in the ends of the connector, respectively, and being movable axially thereof, a spacer fitting within the connector and movable axially thereof and having seating surfaces for spacing the blades axially, said blade shanks having complementary seating surfaces axially rigid therewith and engaging the seating surfaces of the spacer, means for securing the shanks independently in axially adjusted position in the connector with their seating surfaces in engagement with the spacer, cover plates each rigidly connected to the retaining body and to the connector, bolts extending through said plates, and said spacer having openings affording passage of the bolts therethrough in the axially adjusted positions of the spacer.

16. A propeller comprising a tubular retaining body, propeller blades, shanks thereon, a tubular connector extending radially through the body, said shanks fitting in the ends of the connector, respectively, and being movable axially thereof, a spacer fitting within the connector and movable axially thereof and having seating surfaces for spacing the blades axially, said blade shanks having complementary seating surfaces axially rigid therewith and engaging the seating surfaces of the spacer, said spacer having internal peripheral pilot surfaces at its ends, said blade shanks having an external peripheral pilot surface complementary thereto, means for securing the shanks independently in axially adjusted position in the connector with their seating and pilot surfaces in engagement with the spacer, cover plates each rigidly connected to the retaining body and to the connector, bolts extending through said plates, and said spacer having openings affording passage of the bolts

therethrough in the axially adjusted positions of the spacer.

17. A propeller comprising a pair of propeller blades, shanks on the blades, a tubular connector, said shanks fitting in the ends of the connector, respectively, and being movable axially thereof, and rotatable therein about their axes, means for securing the blades in axially and rotatably adjusted positions independently in the connector, a rigid spacer fitting within the connector and movable axially thereof and having seating surfaces for spacing the shanks axially, said shanks having complementary seating surfaces axially rigid therewith and engaging the seating surfaces of the spacer, and means for connecting the connector to a propeller shaft.

18. A propeller comprising a connector having portions which are open at their ends for receiving propeller blade shanks, propeller blades, shanks on the blades receivable in said portions and supported thereby, connecting means for each shank for interconnecting the associated shank and portion of the connector, each of said connecting means including a castellated collar embracing the shank and slidably axially thereof and having a threaded portion coaxial with the shank, said connector portions having complementary threaded portions cooperable with those of the shank, the outer ends of said connector portions being castellated with the notches of the castellations open outwardly of the propeller, a key insertable into aligned notches of the castellations of the collar and connector portion, and with a portion lying along the shank, a clamping ring embracing the castellated portion of the collar and the key for clamping the castellated portion of the collar tightly against the shank and retaining the key in position in said aligned notches.
